ABSTRACT OF THE DISCLOSURE

A coin-operated switch having a housing divided into a switch compartment, a coin box compartment and a coin slide compartment, the coin box compartment being open at one side to slidably receive a coin box recessed therein and having a flange and flange opening cooperating with an opening in the housing to receive a padlock as well as a standard internal coin box lock.

This invention relates to coin-operated switches and the like and particularly to a coin-operated switch which is resistant to opening and pilfering. Such switch boxes are used on various kinds of machines for vending products and services such as coin-operated washing machines and dryers in laundromat operations, coin-operated automobile washing devices and a vast number of other applications.

It is well known that losses from theft and damage to coin-operated machines is relatively high. Coin-operated switches of the past have generally been provided with a coin box which was flush with the main case and with an internal electrical coin-operated switch enclosed within the same housing and compartment as the coin box. Such switches were frequently opened by inserting a bladed tool, such as a screw driver, under the edge of the coin box and prying the cover off of the box or alternatively prying open the switch gear access door and through it, reaching the coin box. These switches were subject to another undesirable feature, namely, that the electrical components were mounted within the box and could be serviced only through the access opening.

I have invented a coin-operated switch which eliminates these problems. In the coin box of my invention, there is no access to the coin box from the switch compartment and the coin box is recessed into the main switch housing or box in such manner that no instrument can reach the cover to pry it off or remove it without the necessary key.

In a preferred embodiment of my invention, I provide a main housing divided into a switch gear compartment, a coin box compartment and a coin slide compartment, said coin box compartment being open at one side to receive a coin box, a coin box slidably in said coin box compartment and having a cover slidably fitting into said coin box compartment and sealing said box in said compartment spaced from the open side, lock means in said cover engaging the main housing, an outwardly extending flange on one edge of said cover lying along a sidewall of the coin box compartment, cooperating openings in said flange and said sidewall adapted to removably receive a padlock, a switch mechanism in the switch gear compartment and a coin slide slidably in the coin slide compartment from an outermost coin receiving position to an innermost actuating position for simultaneously discharging coins into the coin box and actuating the switch mechanism.

Preferably, the switch mechanism is mounted on a plate hinged in the switch gear compartment adjacent the access door to said compartment to permit the entire switch mechanism to be swung out of said compartment on said hinged plate for servicing.

In another embodiment, I provide a removable cover

plate having a flange along one edge and adapted to fit into the coin box compartment in front of the coin box and having an opening in the flange cooperating with the openings in the coin box flange and the main housing to receive a padlock. This cover plate prevents access to the lock means on the coin box until the padlock is removed.

Preferably, I also provide a flange on the inner sidewalls of the coin box compartment against which the coin box cover abuts when locked in place.

In the foregoing general description I have set out certain purposes, objects and advantages of my invention. Other objects, purposes and advantages will be apparent from a consideration of the following description and the accompanying drawings in which:

FIGURE 1 is an isometric view of a coin-operated switch according to a preferred embodiment of my invention;

FIGURE 2 is a longitudinal section through the switch of FIGURE 1;

FIGURE 3 is a section on the line III—III of FIGURE 2; and

FIGURE 4 is a longitudinal section through the switch according to a second embodiment of my invention.

Referring to the drawings, I have illustrated in FIGURES 1 through 3 a coin-operated switch having an outer main housing 10 divided internally into a switch gear compartment 11, a coin box compartment 12 and a coin slide compartment 13. The switch gear compartment 11 is accessible through a side door 14 having a lock 15. The compartment is separated from the coin box compartment and the coin slide compartment by a wall 15a having an opening 16 through which the coin slide actuates the switch mechanism contained therein in the usual manner. The switch mechanism 17 may be any of the conventional and well-known switch mechanisms used for coin operation. The mechanism is mounted on a hinged plate or bracket 18 hinged adjacent the door 14 so that the entire switch mechanism can be rotated on the hinge out of compartment 11 through the door 14 for servicing. The coin slide 20 and supporting mechanism 21 are of any conventional coin slide type and will not be described in detail. The coin box compartment 12 is adapted to receive a coin box 25 having a front plate 26 carrying a forwardly projecting ledge or flange 27 having an opening 28 adapted to cooperate with an opening 29 in the main housing so as to receive a padlock (not shown) therethrough. The front cover plate 26 is provided with a threaded lock 30 which passes through the rear wall 31 of the coin box into a locking nut 32 on the wall 15a. The lock 30 is operated by a key inserted into the keyhead 33. The coin box compartment is provided with an inwardly extending flange 34 on the top and bottom of the compartment to abut against the front cover plate 26 of the coin box so as to prevent insertion of a prying tool behind the front cover. The front cover 26 is also recessed into the coin box compartment 12 so as to leave no exposed edge against which a tool may be effectively used.

The second embodiment of my invention illustrated in FIGURE 4, is identical to that illustrated in FIGURES 1 through 3 in all respects and like parts are numbered with like numbers with the addition of ('). In this second embodiment, there is added a cover plate 40 having a flange 41 with an opening 42 adapted to cooperate with the openings 28' and 29' in the coin box and main housing to receive a padlock. The cover plate 40 projects downwardly in front of the lock 33' so as to prevent any unauthorized tampering with the lock.

The structure described hereinabove effectively prevents pilfering from the coin box of the coin-operated switch without the complete destruction of the coin opera-

tor. It thus eliminates the vast bulk of the pilfering problems which have faced this art arising primarily from prying the cover plate of the coin box away from the main housing or reaching the coin box through the switch gear compartment. In addition to eliminating the pilfering problem, the present invention provides for a structure in which the switch gear can be readily serviced without the problems of difficult accessibility which heretofore formed a part of the difficulties characteristic of such devices.

While I have illustrated and described certain presently preferred embodiments of my invention in the foregoing specification, it will be understood that this invention may be otherwise embodied within the scope of the following claims.

I claim:

1. A coin-operated switch comprising a main housing divided into a switch gear compartment, a coin box compartment and a coin slide compartment, said coin box compartment being open at one side to receive a coin box, a coin box slidable in said coin box compartment and having a cover slidably fitting into said coin box compartment to a point spaced substantially from the open end of said compartment and sealing said box in said compartment spaced substantially from the open side, lock means in said cover engaging the main housing, an outwardly extending flange on one edge of said coin box cover lying alongside a sidewall of the coin box compartment, cooperating openings in said flange and said sidewall adapted to removably receive a padlock, a switch mechanism in the switch gear compartment and a coin slide slidable in the coin slide compartment from an outermost coin receiving position to an innermost actuating position for simultaneously discharging coins into the coin box and actuating the switch mechanism.

2. A coin-operated switch as claimed in claim 1 wherein the coin box compartment is provided with inwardly extending flanges spaced from the open end of the

compartment against which the coin box cover abuts along its edges.

5 3. A coin-operated switch as claimed in claim 1 wherein the switch mechanism is mounted on a bracket hinged in the switch gear compartment so as to move from an operating position within the compartment to a service position out of said compartment.

10 4. A coin-operated switch as claimed in claim 1 having an auxiliary shield member slidable in the coin box compartment in front of said coin box, said shield member having a cover member in front of the coin box cover plate and lock means, a flange on said cover member lying along the flange of said coin box cover and having an opening cooperating with the cooperating openings 15 in the coin box flange and sidewall to receive a padlock.

5 5. A coin-operated switch as claimed in claim 4 wherein the flange on said auxiliary shield is returned upon itself to enclose the coin box flange and sidewall and is provided with openings cooperating with the openings 20 in said coin box flange and housing sidewall to receive a padlock.
